(57) **CLAIM**

The ornamental design for a tuna can liquid extractor, as shown and described.

DESCRIPTION

FIG. 1 is a top front side view of a tuna can liquid extractor showing my new design;

FIG. 2 is a left side view of the tuna can liquid extractor;

FIG. 3 is a right side view of the tuna can liquid extractor;

FIG. 4 is a rear view of the tuna can liquid extractor;

FIG. 5 is a front view of the tuna can liquid extractor;

FIG. 6 is a top view of the tuna can liquid extractor;

FIG. 7 is a bottom view of the tuna can liquid extractor; and,

FIG. 8 is a top front side perspective view of the tuna can liquid extractor in use.

The broken lines in FIG. 8 are illustrative of environmental structure forming no part of the claimed design.
